DESIGN FOR A SPECTACLE FRAME

Altina Barrett and Eric Barrett, Hollywood, Calif.

Application February 26, 1945, Serial No. 118,139

Term of patent 14 years

(Cl. D57—1)

To all whom it may concern:

Be it known that we, Altina Barrett and Eric Barrett, citizens of the United States, residing at Hollywood, in the county of Los Angeles and State of California, have invented a new, original, and ornamental Design for a Spectacle Frame, of which the following is a specification, reference being had to the accompanying drawing, forming part thereof.

Fig. 1 is a side elevational view of a spectacle frame as viewed from one side thereof; and,

Fig. 2 is a side elevational view as viewed from the other side, showing our new design.

The essential features of our design reside in the parts shown in full lines.

We claim:

The ornamental design for a spectacle frame, substantially as shown and described.

ALTINA BARRETT.
ERIC BARRETT.
